UNITARY POT PRESS

Fred S. Carver, Short Hills, N. J.

Application March 27, 1934, Serial No. 717,565
Renewed July 20, 1938

1 Claim. (Cl. 108—50)

This invention relates to presses, and particularly multiple pot presses such as are used for extracting cocoa butter from ground cocoa liquor.

5 *Objects*

It is an object of my invention to provide a press organization wherein the actual pressing of material, to the full capacity of the press, can 10 be going on practically continuously, with very little time in which the press itself is not working, which at the same time calls for a minimum of parts, which requires a minimum of floor space, and which requires little work and time on 15 the part of the operator.

On specific object of my invention is to provide an improved feeding apparatus which contributes in making feasible the above general result.

20 Former practice where the pots were all drawn out to the same side the press was inefficient because the actual pressing was going on for too small a proportion of the time, being interrupted by long periods required for the slow removal 25 of the pressed cakes by hand and the slow re-filling of the press pots by hand. And where other former practice provided two sets of pots for more continuous operations, it was at the cost of providing duplicate slideways on both 30 sides of the press, providing two complete sets of the expensive press pots with their associated parts, directly occupying more floor space because it had two sets of slideway frames, indirectly requiring still more floor space because space had 35 to be provided for the attendant to walk around and unload the press from two sides, and requiring more labor because the operator had to walk back and forth from one side to the other and could not unitarily eject and fill the pots from 40 a single point.

The present invention makes it possible for the press to be operating almost continuously at full capacity and still have only one set of press pots and one set of slideway frames. The operator 45 can always work from one position in front of each press, wherefore the presses can be placed side by side close together, and other presses closely spaced back to back with them, effecting great savings in floor space and labor. Furthermore, as these presses are always heated there 50 is minimum heat loss and the work is kept at the most uniform temperature when each pot is in the press during every pressing operation 55 and when the intervals between pressing opera-

tions are of minimum duration, which results my present construction brings about.

Drawings

In the annexed drawings I have shown an illustrative embodiment of my invention.

Fig. 1 is a front elevation of the press;

Fig. 2 is a side elevation of the press;

Fig. 3 is a horizontal section taken on the line 3—3 of Fig. 2, the closed position of the pots 10 being shown in full lines and their open position being shown in dotted lines;

Fig. 4 is a sectional view on line 4—4 of Fig. 2, of the front half of the press showing the ejecting mechanism;

Fig. 5 is a detail view showing the ejector in 15 down position;

Fig. 6 is a side view showing the feed valve controls;

Fig. 7 is a detail sectional view taken on the 20 line 7—7 of Fig. 3 showing the interengagement of the platens and press pots during pressing.

Fig. 8 is a detail view taken on the line 8—8 of Fig. 6 showing the feed spout in section;

Fig. 9 is a detail view taken on the line 9—9 25 of Fig. 8 showing the return spring for the feed valve;

Fig. 10 is a side elevation, partly in section, on the line 10—10 of Fig. 3, illustrating particularly the stops supporting the series of platens; Fig. 30 11 is a more or less diagrammatic view showing the hydraulic cylinder and piston for actuating the ejectors; and, Fig. 12 is a more or less dia- 35 grammatic view taken on the line 12—12 of Fig. 2 showing the main hydraulic cylinder and ram for carrying out the pressing operation.

The press comprises feet 10, a lower press head 12 containing a conventional hydraulic ram-and-cylinder controlled in the standard way by valve 13 with operating handle 13', an upper press head 14 which is connected to the lower head by strain rods 16, rear frame members 18, and front frame members 20. The frame members are stepped inwardly at successive levels, forming stops 22 which support platens 24.

40 The platens 24 are shaped to ride up and down within the strain rods and be guided thereby. Each platen supports, on compression springs 26, two slideway members 29, bolts 30 holding members 28 in place while allowing them to be 45 squeezed toward the platen. The slideway members provide slideways 29 into which the press pots can be slid, thus providing stations for the pots, which stations are at fixed positions when the press is not under compression and which 50 55

allow vertical movement of the pots when the press is put under compression.

Each pot 32 consists of a ring member 34, and a piston 36 forming a bottom for the pot. The piston bears a filter means 38 in its upper face, and has outlet means 39 to lead away the expressed fluid. A handle 40 is provided at the front edge of each pot for pushing and pulling same in and out.

- 10 Each platen except the lowermost one is provided on its under side with a top closure 42 for the pot beneath. This top closure bears a filter means 44 in its under face, and it is provided with outlet means 45 to lead away the expressed fluid. A similar closure member with filter means is provided on the under surface of the upper head, to serve the topmost pot. The filter means 38 and 44 are preferably but not necessarily permanently attached to the pistons and top closures.

When all the pots are in the press, filled with fluid to be pressed, the main hydraulic ram is raised by opening the main valve 13 by control handle 13'. This valve 13 admits fluid under 25 pressure to the main cylinder in the manner conventional in the hydraulic press art. This first closes in all the platens against the compression of springs 26, thereby tightly engaging each pot ring with the closure member 42 above it so as to close up the pots. Upon further compression the plungers 25 of platens 24 contact the pistons 36 in pots 32, and raise them, thereby pressing the material in the pots.

The front frame members 20 bear slideways 35 21. When pressure is released from the main ram these frame slideways 21 and the press slideways 29 carried by the platens are in alignment.

The press pots are left under pressure for some time, after which pressure on the hydraulic ram 40 is released and the pots are all withdrawn by hand out into the frame 20, whereupon the pressed cakes are ready to be ejected by mechanism provided therefor.

Ejector members 50 are mounted on slide-bars 45 52 in positions immediately below the withdrawn positions of the pots. A yoke 54 connects the top of the slide-bars, and is capable of being raised powerfully by a hydraulic ram-and-cylinder 56, controlled in the conventional way by a valve 58. When the ejector members are raised they eject 50 all the compressed cakes which are then removed by hand. The ejector members are then let back down, the pistons 36 returning to form bottoms for the pots which are then ready for refilling. Means are provided for filling the pots in their 55 withdrawn position, with cocoa liquor or other material to be pressed, which is in a generally fluid state, as follows:

A common feed line 60 from a pump or other 60 source under pressure extends down alongside the pots in their withdrawn position. Branches 62 extend out therefrom and terminate one over each pot. These branches have individual valves 64 each with a handle 66, a crank arm 67, and a spring 68 urging it to closed position. In Fig. 65 the center valve is shown in open position and the others in closed position.

A bar 70 is mounted on the frame by guide-studs 72 secured to the frame and passing 70 through slots 75 in the bar. These studs carry washers 73 and pins 74 which hold the bar on. A pivoted rocker arm 76 has a slot and pin connection 78, 80 with bar 70. Thus as arm 76 is pulled down to the dotted position shown in Fig. 75, bar 70 is raised, its slots allowing such move-

ment. The bar 70 carries a pin 82 for each valve 64, which pin serves as a lug for cooperation with crank arm 67 thereof. When bar 70 is raised by arm 76, all the pins 82 are raised, rotating all the valves to open position, whereby the pots are 5 filled simultaneously.

Thus when the pots are all ready to be filled the operator can pull down arm 76 and hold it down until the pots are all practically full, whereupon he releases the arm 76, and the 10 springs 68 close all the valves. If, due to variations in the consistency of the material or for any reason, the pots do not all fill uniformly, provision is made for easily completing the filling singly to the desired levels. This is accomplished 15 by opening separately the valve 64 of any pot or pots which may not have filled to the same extent as the rest when arm 76 was operated.

When the pots are all filled, they are slid back into the press, where they are ready for the next 20 pressing.

Operation

With this press, mechanically operated in this way, the actual pressing interval occupies nearly 25 all the operating time, and removing and refilling between pressing periods are easy operations requiring very little time.

The operation of the press, starting at the point where the pots are charged and under 30 pressure in the press and continuing through a complete cycle back to the same point, is as follows:

When the pressing is completed the operator actuates valve handle 13' to release the pressure, 35 whereupon the platens, which support the pots, descend until stopped by the stops 22. Then the operator pulls the pots out by their handles to withdrawn position.

Next he turns on valve 58 which raises the 40 ejectors, and removes the cakes which are then free and clear of the pots. Then he reverses valve 58, letting the ejectors sink back, and the pots are ready for refilling.

With the pots remaining in withdrawn position 45 the operator pulls down the rocker arm 76, which turns on the feed valves for all the pots. When they are all filled to the proper level he allows handle 76 to go back and all the valves to close under the action of springs 68. If any of the 50 pots have not filled as fast as the rest he brings them up to just the desired level by the individual valve handles 66.

When all the pots are filled he pushes the pots 55 into the press and actuates main valve 13 by handle 13' to apply hydraulic pressure.

The cycle has then been completed and this press will require no more attention until the end of its pressing period. Hence the operator can now empty and recharge other similar presses 60 seriatim returning to this press when the material has been under pressure long enough.

Particular attention is drawn to the fact that on the one hand this press is working at its maximum capacity during all the time except 65 the short interval required for mechanically discharging and recharging, giving the advantages of the form of prior art construction which has gone into general use, and on the other hand all the operations are carried on at one side of the press, giving the advantage of another form of prior art construction. Heretofore it has not been found possible to secure all these different advantages at the same time in a single press.

A press as shown herein will turn out about 75

the same quantity of work as the press shown in my patent No. 1,607,722, issued Nov. 23, 1926, which, besides having a greater number of parts and requiring more floor space, required the operator, in going through a pressing cycle, to make several trips from side to side of the press and up and down steps at each side in order to reach and serve the different pots separately. The unitary press of the present invention is operated entirely from one side, all the pots undergo pressing together, and they are all emptied and refilled together, with a saving of labor, time, parts and floor space. Thus it will be seen that the present invention represents an important step forward.

While I have shown and described the pots as pushed in and pulled out individually by hand, it will be appreciated that the press arrangement of my invention need not be confined to manual moving of the pots nor to separate individual moving of the pots, but that other and more or less equivalent means may readily be used in this connection.

While I have shown and described a particular embodiment of my invention, it will be understood that modifications and variations thereof may be made, wherefore I wish to be limited only to the scope of the appended claim.

I claim :

- 30 In a vertical hydraulic pot press, a predetermined plurality of pot stations into and out of which the pots are laterally slideable at one side providing means for supporting the pots at fixed

positions when the press is not under compression and allowing vertical movement of the pots when the press is put under compression, the same predetermined plurality of platens, the same predetermined plurality of pistons, each 5 pot station being positioned between a platen and a piston, the same predetermined plurality of laterally extending slideways aligned with the pot stations when the press is not under compression and all extending out to the same one 10 side of the press only, means for ejecting cakes from all the pots simultaneously when in out position on said slideways with unitary means of control for all the ejecting means, filling means for filling all the pots simultaneously when in 15 out position on the slideway, unitary control means for all of said feed means and individual control means for each thereof, whereby all the pots in the set may be simultaneously subjected to pressure application, and between pressure 20 applications all the pots in the set can be moved to the outer stations, all the cakes simultaneously ejected, and all the pots simultaneously filled and correction made for lack of evenness in filling, and all of the pots returned to the 25 pressing station and the pot is in the pressing station for a time greatly in excess of such time as it is out, and all of the emptying and refilling operations can be performed at one place and in a short space of time, leaving the press under 30 compression and the operator free during all the rest of the time.

FRED S. CARVER.
